Primary Examiner — Mark Goodwin(74) *Attorney, Agent, or Firm* — Marshall, Gerstein & Borun LLP(57) **CLAIM**

The ornamental design for a boom nose, as shown and described.

DESCRIPTION

FIG. 1 is a front, top, and side perspective view of a boom nose showing our new design.

FIG. 2 is a front, top, and opposite side perspective view thereof.

FIG. 3 is a front elevation view thereof.

FIG. 4 is a side elevation view.

FIG. 5 is an opposite side elevation view.

FIG. 6 is a rear elevation view; and,

FIG. 7 is a top plan view.

The bottom view forms no part of the claimed design.

The broken line showing represent elements of the boom nose that do not form part of the claimed design.
